UNITED STATES PATENT OFFICE.

EDWARD J. OUELLETTE, OF ANACONDA, MONTANA.

APRON FOR ORE ELEVATOR FEEDERS.

Application filed November 28, 1925. Serial No. 72,059.

My invention relates to an apron for a feeder for traction elevators, which are adapted to effect approximately a vertical lift, and it consists in the combinations, constructions and arrangements herein described and claimed.

An object of the invention is the provision of an apron which will function to prevent loose material from dropping from the discharge end of a launder or other spout between the end of the launder and the ascending buckets of the traction elevator, but which will yield in response to a relatively great stress, as when a relatively large object lodges between the face of the apron and a bucket of the elevator, thus preventing injury to the elevator or to the apron.

A further object of the invention is the provision of an apron of the character described which will return automatically to position close to the path of movement of the ascending buckets of the elevator with which the apron is associated after the apron has been forced away from such position by a relatively great stress.

A further object of the invention is the provision of an apron of the character described, which will cooperate with a plurality of adjacent ascending buckets of the elevator to prevent passage of loose material from the launder or other discharge spout between the apron and said buckets.

A further object of the invention is the provision of an apron of the character described, which is adapted to cooperate with the discharge end of the associated launder and with the bucket of the elevator which passes the discharge end of the launder to prevent spawls or other relatively large objects from protruding from the bucket over the edge of the latter.

An important object of the yielding apron is to prevent damage to the feed box should the top outlet of the elevator become choked, causing the feed to fall back down into the bottom of the shaft and accumulating under the bottom pulley in the "boot". During such an event the crushed rock, spawls, etc., are dredged up by the buckets on the belt, and hauled up to the dump plate and fall back down the shaft and into the "boot" again. Large numbers of oversize rock are caught between the edge of the buckets and the face of the plate. This plate, because of its mounting, springs back and allows the

rock fragment or spawl to fall into the following bucket or into the "boot" again, thus the elevator is not damaged by the feeder system nor is my feeder system damaged by the elevator.

In every installation of my feeders I strongly advise that precautions be taken to prevent the choking of the top outlet of the elevator. This can be done by providing the elevator with extra large outlet, or by having the emergency outlet to dump the feed onto the top floor of the mill instead of allowing it to fall back down the shaft. If allowed to dump on the floor the attendant would soon discover and correct the situation.

If the suggestion above is carried out it is possible to use a cheap hard cast bucket as there is then no chance of buckets being subjected to great shocks or strains and the resulting economies making the Ouellette feeders a profitable investment.

Other objects and advantages of the invention will be apparent from the following description, considered in conjunction with the accompanying drawings, in which:

Figure 1 is a view mainly in vertical section, and partly in side elevation, showing one form of apron and supporting means therefor in association with the ascending buckets of a traction elevator, and with a feed plate for conducting materials to such bucket.

Figure 2 is a side elevation of the improved apron and its mounting.

Figure 3 is a side elevation of a second form of apron and its mounting in association with a feed plate and with ascending buckets of a traction elevator.

Figure 4 is a longitudinal vertical section through the apron and the mounting therefor which are exhibited in Figure 3.

Figure 5 is a plan view of the supporting and operating means for the apron exhibited in Figures 3 and 4.

Figure 6 is a view similar to Figure 1, showing another form of apron and mounting therefor.

Figure 7 is a plan sectional view of the structure exhibited in Figure 6, showing also a pair of side guards associated with the feed spout of the assembly, a portion of the bottom of the feed spout being broken away,

Figure 8 is a view similar to Figures 1

and 3, showing another form of apron and mounted in association with a feed plate and the ascending buckets on the elevator.

Figure 9 is a section substantially on the line 9—9 of Figure 8, which is in the direction of the arrows, and

Figure 10 is a fragmentary vertical sectional view through the delivery structure at the upper end of the elevator, illustrating the means for preventing clogging and choking of the main discharge launder at the upper end of the elevator.

The apron exhibited in Figures 1 and 2 comprises a body portion 1 having the form of a plate which is disposed vertically edge-wise and is provided at its upper edge with an upwardly and rearwardly turned flange or edge portion 2, and at its lower end with a downwardly and rearwardly inclined flange or lower edge portion 3. A screw threaded attaching stud 4 extends rearwardly of the central portion of the body 1 of the apron and has a flange 5 at its inner end apertured for the reception of fastening devices, such as the bolts and nuts indicated at 6, which secure the attaching member firmly to the body portion 1 of the apron. The end portions of the fastening devices 6 at the front of the body portion 1 of the apron are countersunk so as not to extend beyond the plane of the front face of the latter.

The apron is movable bodily within the limits at an oblique angle between the inclined lower end portion 7 of a feed plate 8, which may be the bottom of a feed spout or launder, not shown, or other suitable conduit for supplying crushed rock, ores, or other similar material to the buckets, and a lower inclined baffle or guard plate 9 which is parallel to the portion 7 of the feed plate. The upwardly and rearwardly turned flange 2 at the upper end of the body of the apron is substantially parallel to the discharge end portion 7 of the feed plate and may carry a renewable wear plate 10, which will move close to the under face of the portion 7 of the feed plate when the apron is moved upwardly and rearwardly from the position shown in Figure 1. At the same time, the lower edge of the downwardly and rearwardly inclined flange 3 will move in a plane parallel and close to the lower baffle plate 9.

A supporting and guide arm for the apron includes a straight section 11 which extends slidably through renewable bushings 12 which are secured in aligned openings in the inclined upper end portions of spaced arms 13 and 14, respectively, of a bracket 15 that is secured at 16 to a stationary support 17. The supporting and guide arm for the apron also includes an angular section 18 which is shown as being a tubular elbow that is threadedly engaged at one end with the adjacent end portion of the straight sec-

tion 11 of the supporting and guide member and is threadedly engaged at its opposite end with the stud projection 4. The upper end portions of the arms 13 and 14 of the bracket 15 may support lubricant cups 19 which are adapted to feed lubricant through suitable apertures in the bushings 12 to the relatively moving surfaces of the bushings and the straight section 11 of the supporting and guide arm for the apron.

Stop collars 20 are secured, as by means of set screws 21, to the straight section 11 of the supporting and guide arm for the apron above the inclined upper end portions of the bracket arms 13 and 14, and cooperate with said bracket arms to limit the downward and forward movement of the supporting and guide arm for the apron, and therefore to limit the movement of the body portion 1 of the apron toward the path of movement of the ascending buckets 22 which are secured on the outer face of an elevator belt 23, as shown in Figure 1. The belt 23 is trained about a pulley 24 which is supported to turn about a horizontal axis and the path of movement of the ascending buckets of the elevator will pass close to the front face of the body portion 1 of the apron when the apron is at the limit of its downward and outward movement as shown in Figures 1 and 2. It is obvious that gravity will tend to hold the apron at the limit of its downward and outward movement. However, I prefer to make use of an expansion spring 25 which is coiled about the straight section 11 of the supporting and guide arm between the lower stop collar 20 and the inclined upper end portion of the bracket arm 13 and which will function to positively assure the return of the apron to the position shown in Figures 1 and 2 after the apron has been forced from such position by a relatively great stress.

When the apron is at the limit of its downward and outward movement, which is the normal position thereof, the rearwardly and upwardly inclined flange or upper edge portion 2 of the apron will extend rearwardly and upwardly beyond the edge of the lower end portion 7 of the discharge member of the feeding mechanism with which the apron may be associated. The downwardly and rearwardly inclined flange or lower edge portion 3 of the apron will lie in a plane which is located rearwardly of the inclined lower baffle plate 9. The latter may be supported on arms such as indicated at 26 and 27 respectively, extending from the hereinabove mentioned stationary support 17, and this plate 9 may have a renewable wear resisting face covering if desired. The height of the body portion of the apron is greater than the distance between the adjacent ends of adjacent buckets 22 of the elevator with which the apron is associated

so that each ascending bucket of the elevator will be in operative position with respect to the front face of the body portion of the apron before the bucket next thereabove has 5 passed completely above the level of the upper end of the body portion of the apron. It therefore will be manifest that the apron will act in conjunction with the feed plate, and the buckets on the ascending side of 10 the elevator to prevent loose material from falling from the feed plate between the buckets or belt of the elevator and the feed plate into the bottom of the shaft in which the lower end portion of the elevator is 15 located, and from which the material is to be lifted by means of the elevator. Moreover, the apron will act to prevent material which enters the bucket from extending over the edge of the bucket to position to come 20 into contact with a stationary part at a higher level in the shaft which might cause injury to the elevator. Should a relatively large object, such as a large piece of rock, pass from the feed plate to position to enter 25 the bucket and be too large for the bucket to carry, the pressure of such relatively large object on the apron will cause the spring 25 to yield and the apron will move upwardly and rearwardly, thus permitting 30 the relatively large object to fall to the bottom of the shaft without causing injury to the elevator and without stopping the operation of the elevator.

The apron exhibited in Figures 3 and 4 35 comprises a body portion 30 having the form of a plate disposed vertically edgewise and having a rearwardly extending flange 31 at its upper end, on which a renewable wear plate 32 is secured by fastening devices 33 or other suitable known means. The apron body is supported at the forward end of a 40 longitudinally movable supporting and guide rod 34 which is slidble in alined bushings 35 that are secured in openings in bearings at the upper ends of spaced arms 36 of a bracket 37. The latter is secured, as at 38, on a stationary support 39. The supporting and guide member 34 has a flange 40 at the forward end thereof apertured for the reception of fastening devices 41, whereby the body portion 45 30 of the apron is secured firmly to the supporting guard arm 34 at the forward end of the latter. Lubricant receptacles such as indicated at 42 may discharge through suitable 50 openings to the relatively moving surfaces of the supporting and guide member 34 and the bushings 35. A stop collar 43 which is secured on the rearward end portion of the supporting and guide member 34, as by means of a set screw 44, will cooperate with the adjacent bracket arm to limit the forward axial movement of the member 34, and therefore the movement of the body of the apron toward the path of movement of the 55 ascending buckets 45 which are carried by

the belt 46 of the traction elevator with which the apron is associated. The inwardly turned flange 31 at the upper end of the body of the apron extends rearwardly beyond the edge of a feed plate 47 which may be the bottom of the discharge end portion of the launder or other chute for delivering crushed rock, ores, or other materials to the ascending buckets of the traction elevator. The body of the apron carries a rearwardly 70 extending guide arm 48 which extends slidably through an opening 49 in the adjacent bracket arm 36 and engages with the latter to prevent the apron from being turned about the axis of the supporting and 75 guide member 34, the guide arm 48 being parallel with the guiding and supporting arm 34. The means for returning the apron to the limit of its movement in a forward direction and for yieldingly resisting movement of the apron away from the path of movement of the ascending buckets may 80 comprise a bell crank 50 having a hub portion thereof disposed between upstanding lugs 51 on a supporting plate 52 and connected with such lugs by means of a horizontal pivot element 53, which extends through alined openings in the lugs 51 and the bore of the hub of the bell crank. Pivot element 53 is retained against accidental displacement axially in any suitable known manner 85 as by means of retaining collars 54 which are secured at 55 on the extreme end portions of the pivot elements 53. One arm of the bell crank 50 extends upward as indicated at 100 56, and is pivotally attached at its upper end at 57 to one end of a link 58, which is pivotally attached at its opposite end at 59 to the rearward end portion of the guiding and supporting arm 34 for the apron. The 105 other arm of the bell crank is substantially horizontal and is a straight spring bar indicated at 60 which extends in the general direction of the apron substantially at right angles to the arms 56 of the bell crank. The 110 spring arm 60 supports a weight 61 which is slidble therealong and can be secured to the spring arm in adjusted position on the latter by means of a set screw 62. Obviously, the weight will act to urge the spring arm 115 60 downward and therefore will tend to swing the arm 56 of the bell crank toward the apron. The apron thus will be retained at the limit of its forward stroke until a pressure sufficient to overcome the resistance 120 of the weighted spring arm has been imposed on the apron body, tending to move the apron rearwardly. Such pressure on the apron body may result from the falling of a relatively large object, such as a large piece 125 of rock, from the feed plate 47 or to one of the buckets 45 and thence against the front face of the apron body. This resistance of the rearward movement of the apron can be varied by adjusting the position of the 130

weight 61 along the spring arm 60, and it of course will be understood that the spring arm is sufficiently stiff to sustain the weight which it carries without appreciable flexure under normal operating conditions.

The apron exhibited in Figures 5 and 6 comprises a body portion 70 having the form of a plate that is disposed vertically edge-wise and has a rearwardly extending flange 71 at its upper edge on which a renewable wear plate 72 is secured. A supporting and guide arm 73 extends rearwardly from the central portion of the body 70 of the apron through aligned openings in spaced upstanding arms 74 and 75 respectively, of a bracket 76. The bracket 76 is secured, as at 77, on a stationary support 78. A compression spring 79 that is coiled about the supporting and guide arm 73 between the bracket 75 and a stop collar 80 that is secured on the supporting and guide member 73 between the bracket arms 74 and 75, tends to urge the supporting and guide arm 73 in a forward direction, and thus tends to resist inward movement of the apron body from position close to the path of movement of the ascending buckets 81 of a traction elevator which is adapted to effect a vertical lift, and which includes the belt 82 on which the buckets are supported. The body portion 70 of the apron also may have a rearwardly extending guide arm 83 which extends slidably through an opening 84 in the adjacent bracket arm 74, and cooperates with the wall of the opening 84 to prevent the apron from turning about the axis of the supporting and guide arm 73. The rearwardly turned flange 71 at the upper end of the body of the apron extends beyond the edge of the discharge end portion of an inclined feed plate 85 with which the apron is associated, and which is adapted to discharge materials over the wear plate 72 into one of the buckets 81 of the traction elevator. The height of the body portion 70 of the apron is greater than the distance between adjacent buckets 81 of the elevator.

The feed plate 85 may be the bottom of a trough shaped launder or chute, and as shown in Figure 7, vertical blocks 86 may be disposed at the sides of this feed chute, at the discharge end of the latter between said sides of the feed chute and outwardly offset portions 87 of side guards 88 which are secured, as at 89, to the sides of the feed chute, whereby material will be prevented from spilling from the feed chute or over the end edges of the structure at the upper end of the apron. The side guards 88 have the outwardly offset portions 87 extending in flanking relation to the path of movement of the ascending buckets, and the side guards may have the extreme forward end portions thereof further offset outwardly as indicated at 90 to clear the adjacent peripheral edge

portion of a pulley 91 over which the belt 82 of the elevator passes.

The operation of the form of the device exhibited in Figures 6 and 7 is identical in essential respects with the operation of the forms of the device which have been hereinabove described.

In the assemblies shown in Figures 8 and 9, an apron 100 is shown as being a plate disposed vertically edge-wise to the path of ascending buckets 22 on the belt 23 of the hereinbefore mentioned traction elevator. The plate 100 is attached to the lower end portions of a pair of swinging hanger bars 101 by means of upper and lower pairs of brackets 102 and 103 respectively, the brackets 102 having arms secured to the lateral edge portions of the plate 100 adjacent to the upper end of the latter and having arms 102^a extending slidably through arcuate slots 104 in the side walls 105 of a box like structure, generally designated 106. The lower brackets 103 are attached to the side edge portions of the plate 100 adjacent to the lower end of said plate and have arms 103^a which extend slidably through arcuate slots 107, in said side walls 105 of the box like structure 106. The arms 102^a and 103^a are secured to the hanger bars 101. The hanger bars 101 have aligned openings relatively adjacent to, but spaced from their upper ends, for the reception of a horizontal supporting rod 108 which has the end portions thereof supported by suitable stationary supports, such as indicated at 109. A cross bar 110 extends across the extreme upper end portions of the hanger bars 101. A retractile spring 111 connects the rod 110 with a fixed support 112 and serves to return the hanger bars 101 and the apron 100 from the dotted line position indicated in Figure 8 to the full line position of Figure 8. The apron 100 carries a rearwardly extending flange 113 on to which material may be discharged from the downwardly inclined outer end portions 114 of a horizontal feed plate 115. The side plate 115 is supported within the box like structure 106 between the side walls 105 and below the discharge end of a chute 116. The box like structure 106 is open at the side thereof next to the elevator and may have a bottom 117 on which are disposed spaced stops 118 and 119 respectively. These stops are adapted to engage with the lower end of the apron 100 to limit the swinging of the latter. The operation of the form of device shown in Figures 8 and 9 is identical in essential respects with the previously described forms of the device.

It is desirable that the outlet for material at the top of the elevator should not be permitted to be choked, which would result in the material falling back into the bottom of the shaft and accumulating under the lower pulley of the elevator designated 120.

- The material from the buckets 22 is passed from the buckets as they pass over the pulley 120 into the discharge chamber 121. This discharge chamber has a bottom wall 122 and a vertical wall 123 against which the material may be thrown from the buckets. A discharge launder or conduit 124 leads from an opening 125 in the lower end of the wall 123 and is inclined downwardly.
- 5 10 15 20 25 30 35 40 45 50 55 60 65 70 75 80 85 90 95 100 105 110 115 120 125 130
- An inclined baffle 126 is provided on the bottom wall 122 at the edge of the latter which is nearest to the elevator and prevents the material from falling from the discharge chamber 121 into the shaft 127 of the elevator, so long as there is not an undue accumulation of material within the chamber 121, the upper edge of the baffle 126 being slightly higher than the level of the upper edge of the opening 125.
- However, it is obvious that any clogging of the main delivery of the discharge conduit 124 would result in accumulation of material in the chute 121 and that the material would fall from the mass thereof in the chamber 121 into the shaft 127 after the material in the chamber 121 was piled up therein above the level of the upper edge of the baffle or guard plate 126. I, therefore, provide an auxiliary delivery conduit or outlet 128 which opens into the chamber 121 between the inclined baffle 126 and the plane of the adjacent wall of the elevator shaft 127. Therefore in the event that the main discharge conduit 124 becomes choked, the overflow of the material which accumulates in chamber 121 through the auxiliary outlet 128 and will fall onto a lower floor 129 where such material is likely to attract the attention of an operator of the device and because of the undue accumulation of the material in the discharge chamber 121 can be quickly removed.
- Obviously the invention is susceptible of embodiment in forms other than those which are illustrated in the accompanying drawings, and I therefore consider as my own all such modifications and adaptations thereof as fairly fall within the scope of the appended claims.
- 70 I claim:—
1. In combination, a traction elevator having buckets for effecting a vertical lift of loose materials, a feed member having the discharge end thereof proximate to the path of movement of the buckets on the ascending side of the elevator, and a yielding apron associated with said feed member for guiding materials from said feed member into a bucket of said elevator.
  2. In combination, a traction elevator having buckets for effecting a vertical lift of loose materials, a feed member having the discharge end thereof proximate to the path of movement of the buckets on the ascending side of the elevator, an apron for deflecting materials from said feed member into a bucket of said elevator, and yielding means resisting movement of said apron away from the path of movement of the ascending buckets of the elevator.
  3. In combination, a traction elevator having spaced buckets for effecting a substantially vertical lift of loose materials, a feed member adapted to discharge into the path of movement of the buckets on the ascending side of said elevator, and a yielding apron having a body portion disposed in the plane between the path of movement of said ascending buckets and the discharge end of the feed member and below the level of the discharge end of said feed member.
  4. In combination, a traction elevator having spaced buckets for effecting a substantially vertical lift of loose materials, a feed member adapted to discharge into the path of movement of the buckets on the ascending side of said elevator, an apron having a plate-like body portion, means for supporting said body portion vertically edgewise in the plane between the path of movement of the ascending buckets of the elevator and the discharge end of said feed member, said apron having a rearwardly extending flange at its upper end extending rearwardly of the discharge end of said feed member.
  5. In combination, a traction elevator having spaced buckets for effecting a substantially vertical lift of loose materials, a feed member adapted to discharge into the path of movement of the buckets on the ascending side of said elevator, an apron having a plate-like body portion, means for supporting said body portion vertically edgewise in the plane between the path of movement of the ascending buckets of the elevator, and the discharge end of said feed member, said apron having a rearwardly extending flange at its upper end extending rearwardly of the discharge end of said feed member, and a renewable wear plate superimposed on said flange of the apron.
  6. In combination, a traction elevator having spaced buckets for effecting a substantially vertical lift of materials, an inclined feed member for feeding materials to said buckets, an inclined baffle plate located at a lower level than the discharge end of said feed member and substantially parallel to the latter, an apron movable between said lower baffle plate toward and away from the path of movement of the ascending buckets on said elevator.
  7. In combination, an elevator including a flexible carrying member and spaced buckets on the carrying member, said elevator being adapted to effect a vertical lift of loose materials, a feed member arranged to discharge in the path of the ascending buckets of the elevator, and a yielding apron

having a body portion supported in a plane between the discharge end of said feed member and the path of movement of said buckets; said body portion of the apron being located below the level of the discharge end of the feed member and having a height greater than the distance between adjacent buckets of said elevator.

8. In combination, a traction elevator having spaced buckets for effecting a substantially vertical lift of materials, an inclined feed member for feeding materials to said buckets, an inclined baffle plate located at a lower level than the discharge end of said feed member and substantially parallel to the latter, an apron movable between said lower baffle plate toward and away from the path of movement of the ascending buckets on said elevator, said apron comprising a body portion of plate-like form disposed substantially parallel to the path of movement of the ascending buckets of the elevator and having a rearwardly and upwardly inclined flange at its upper end extending beyond the discharge end of said feed member, said body portion having a downwardly and rearwardly turned flange at its lower end extending close to the plane of the lower baffle member, a supporting member having a pair of spaced arms including inclined upper end portions having aligned openings, a supporting and guiding arm attached to said apron body and extending slidably through the openings in the arms of said supporting member, means for limiting the sliding movement of said guiding and supporting arm in the openings in the arms of said supporting member, and spring means urging said apron toward the path of movement of the ascending buckets of said elevator.
9. In combination, a traction elevator having spaced buckets for effecting a substantially vertical lift of materials, an inclined feed member for feeding materials to said buckets, an inclined baffle plate located at a lower level than the discharge end of said feed member and substantially parallel to the latter, an apron movable between said lower baffle plate toward and

away from the path of movement of the ascending buckets on said elevator, said apron comprising a body portion of plate-like form disposed substantially parallel to the path of movement of the ascending buckets of the elevator and having a rearwardly and upwardly inclined flange at its upper end extending beyond the discharge end of said feed member, said body portion having a downwardly and rearwardly turned flange at its lower end extending close to the plane of the lower baffle member, a supporting member having a pair of spaced arms including inclined upper end portions having aligned openings, a supporting and guiding arm attached to said apron body and extending slidably through the openings in the arms of said supporting member, means for limiting the sliding movement of said guiding and supporting arm in the openings in the arms of said supporting member, and spring means urging said apron toward the path of movement of the ascending buckets of said elevator.

10. In a feeder for a traction elevator having buckets for effecting a substantially vertical lift, a feed spout, an apron placed under the discharge end of the feed spout for guiding the material from the spout into the buckets, said apron being mounted to yield away from the buckets.

11. In a feeder for a traction elevator having buckets for effecting a substantially vertical lift, a feed spout, and a yieldable apron mounted under the discharge end of the spout for guiding material from the feed spout into the adjacent bucket and movable away from the buckets, the apron being of a height greater than the distance between the adjacent ends of adjacent buckets.

12. In a feeder for a traction elevator having buckets for effecting a substantially vertical lift, means for delivering material to the buckets, and an apron below the delivering means and adapted to yield away and upward from an adjacent bucket of the elevator.

EDWARD J. OUELLETTE.
